UNITED STATES PATENT OFFICE

114,358

DESIGN FOR A VEHICLE ORNAMENT OR SIMILAR ARTICLE

John D. Wilson, Grosse Pointe, Mich., assignor to Packard Motor Car Company, Detroit, Mich., a corporation of Michigan

Application October 11, 1938, Serial No. 80,388

Term of patent 14 years

To all whom it may concern:

Be it known that I, John D. Wilson, a citizen of the United States, residing at Grosse Pointe, county of Wayne, State of Michigan, have invented a new, original, and ornamental Design for a Vehicle Ornament or Similar Article, of which the following is a specification, reference being had to the accompanying drawing, forming a part thereof, and in which:

Fig. 1 is a perspective view of the left side of a vehicle ornament showing my new design;

Fig. 2 is a perspective view of the right side thereof.

The present design is characterized by the transparent, relatively narrow wing element, the upper and lower edges of which are parallel for approximately two-thirds of its length and the rear end of which extends well beyond the attaching portion of the pedestal, as shown.

I claim:

The ornamental design for a vehicle ornament or similar article, as shown and described.

JOHN D. WILSON.
